UNITED STATES PATENT OFFICE

164,525

MOBILE REFRESHMENT STAND

Albert E. Umholtz, Oklahoma City, Okla.

Application June 26, 1950, Serial No. 10,764

Term of patent 7 years

(Cl. D13—1)

To all whom it may concern:

Be it known that I, Albert E. Umholtz, a citizen of the United States, residing at Oklahoma City, in the county of Oklahoma and State of Oklahoma, have invented a new, original, and ornamental Design for a Mobile Refreshment Stand, of which the following is a specification, reference being had to the accompanying drawing, forming part thereof.

Figure 1 is a perspective view of a mobile refreshment stand, showing my new design; and

Figure 2 is a top plan view thereof.

Figure 3 is a side elevational view; and

Figure 4 is another side elevational view of the same as it appears when observed from the side opposite to that shown in Figure 3.

The rear of the mobile refreshment stand is conventionally plain.

I claim:

The ornamental design for a mobile refreshment stand, as shown and described.

ALBERT E. UMHOLTZ.
